UNITED STATES PATENT OFFICE.

CHARLES H. LEWIS, OF SYRACUSE, NEW YORK.

OIL BURNER.

Application filed October 27, 1921. Serial No. 510,858.

To all whom it may concern:

Be it known that I, CHARLES H. LEWIS, a citizen of the United States, residing at Syracuse, in the county of Onondaga and 5 State of New York, have invented certain new and useful Improvements in Oil Burners, of which the following is a specification.

This invention relates to improvements in 10 oil burners, designed for use in connection with steam generators, furnaces, cooking and heating appliances, and the like, and has for its object to provide a vapor-fuel generator which is novel, simple and compact in construction, which produces the maximum heat by the consumption of a minimum of fuel, and which burns the fuel without any waste or odor. A further object is to provide a burner of the class, which 15 effects its own vaporization of the liquid fuel, and feeds the vapor by gravity to a plurality of jet-burners which are located below the vaporizing chamber, and wherein the flames from the jets envelop the vaporizing member which is disposed between the jets and the boiler or other element to be heated. A further object is to provide novel and simple auxiliary heating means for warming-up the burner parts and for effecting the initial vaporization of the liquid 20 fuel. A further object is to provide means whereby the several jet-burners may be operated singly or in multiples. And a further object is to provide novel heat-and-flame deflectors for spreading the flames rising from the jets for evenly distributing the heat to boilers and the like.

I attain these objects by the means set forth in the detailed description which follows, and as illustrated by the accompanying drawing, in which—

Figure 1 is a top-plan view of the complete device embodying my improvements. Fig. 2 is a front side elevation of the same, 45 which includes a fragment of a boiler. Fig. 3 is an end elevation. Fig. 4 is a central vertical cross-section, taken on line 4—4 of Fig. 2. And Fig. 5 is a central vertical section through one of the valve-controlled jets. 50 In the drawings, 2 represents the base of the burner, comprising a relatively large shallow rectangular hopper-like pan, which supports all of the vaporizing and gas-burning parts within the margins of its normally 55 open top, and 2' represents similar aper-

tured lateral integral extensions by which the device may be handled as well as secured to a support. The four inner corners of the pan are provided with similar integral bosses or pedestals 2^a, whose height corresponds to the top margins of the pan. These bosses serve as point contacts for supporting all of the other burner parts. 3 represents an annular gas or vapor reservoir, which is directly supported upon the bosses 2^a by 60 means of radial integral lugs 3', which extend beyond the periphery of the body 3. The lugs 3' register with the bosses 2^a and are perforated to receive screws 3^x, which are driven into threaded holes in the tops 65 of the bosses, for rigidly holding all of the burner parts together. The interior of the reservoir 3 comprises a continuous unrestricted passage 3^a for the gas or vapor. This annular part 3 receives the gas or 70 vapor by means of a plurality of radial or diametrical conduits or hollow arms 3^b and 3^c, all of which intersect at the common center of the ring 3. The arms 3^b—3^c are preferably cast integrally with the reservoir, 75 and all of said parts are preferably disposed in a common horizontal plane, as shown in Figs. 2, 3 and 4. By providing a number of the arms 3^b—3^c, the gas is conducted to the four cardinal points of the reservoir 80 simultaneously. 4 represents a vertical feed pipe, which rises from the center of the reservoir 3, the lower end of said pipe being tightly screwed into a threaded hole 3^d, which communicates with all of the arms 85 3^b—3^c. The upper threaded end of the pipe or pedestal 4 screws into an opening 5' in the bottom side of a hollow elevated body 5, the said pipe preferably being the sole support for said body. The part 5, herein-after referred to as the vaporizer, is hollow 90 throughout its length for providing a relatively large vaporizing chamber 5^a, as shown in Figs. 3 and 4. One end of the vaporizer 5 is closed, while the opposite end 100 has a threaded opening 5^b to receive one end of an oil-supply pipe 6, which may receive the oil from a tank (not shown) or other source by gravity. The oil (preferably kerosene), shown at 7 in Fig. 4, upon 105 entering the chamber 5^a of the vaporizer, lies at the bottom of said chamber until it is vaporized by the action of the heat, as will presently appear, and for this purpose, the top end 4' of the pipe 4 preferably ex- 110

tends some distance above the inner bottom surface of the body 5 (see Figs. 2, 3 and 4). The vaporizer 5 may be made in any convenient form, but the chamber 5^a is preferably disposed in a horizontal plane, so that the unvaporized oil may spread evenly over the bottom of the chamber 5^a. The vapor resulting from the heating of the oil 7 fills the empty space in the body 5, and when its pressure becomes strong enough the gas or vapor is forced downwardly through the pipe 4, which is the sole outlet for the chamber 5^a, into the cross-arms 3^b—3^c, and thence into the annular reservoir cavity 3^a. The heat for initially vaporizing the kerosene 7 is preferably derived from alcohol 2^x, which is poured into the pan 2 and ignited in advance of the regular firing of the burner. Enough of the alcohol should be placed in the pan 2 to insure the thorough warming-up of all of the burner parts which are supported above the pan 2. By the time the alcohol 2^x is all consumed, the temperature of the vaporizer 5 is sufficient to start the vaporizing of the oil 7. In order to provide in a suitable manner for the subsequent and continuous heating of the vaporizer 5, certain of the radial arms, as 3^b, are fitted with jet-burners 3^f, which are disposed directly beneath the elongated vaporizer 5. Any suitable number of the jets 3^f may be provided, and they may be spaced equidistantly or otherwise from the pipe 4 (see Figs. 1, 2 and 4). As soon as the vaporized oil begins to escape through the jets 3^f, the flames of the alcohol 2^x ignites the vapor, and thereafter, as long as the kerosene 7 is supplied to the chamber 5^a, the jets 3^f will continue to burn with an intense heat and maintain the vaporizer at the proper temperature for effecting the volatilization of the oil. The kerosene 7 is preferably fed to the vaporizer 5 through a common needle-valve (not shown), which may be located in the pipe 6, and by means of which the feed may be safely and properly regulated, in a well-known manner. The gas flames which rise from the jets 3^f strike against the bottom surface of the body 5, and then spread and substantially envelop the said part, and these flames, or the heat therefrom, continue to rise above the vaporizer 5 for heating a relatively large area of a boiler or other part, as 8, which may be positioned above the burner (see Fig. 2). The gas which flows from the arms 3^b—3^c into the annular reservoir 3, is burned by means of a plurality of jets 9, which are preferably positioned at more or less regular intervals around the top side of the reservoir 3, as best seen in Fig. 1. The jets 9 are preferably controlled by similar cocks or valves 9^e, each cock having a handle 9^d by which it is manipulated. The lower ends 9^e of the valve-bodies are screwed into threaded open-

ings in the top side of the reservoir (see Fig. 5) for drawing the vapor from the passage 3^a. Above each cock 9^e is disposed a horizontal preferably disc-shaped deflector or spreader 10, against whose underside the flames from the jets 9 strike. The deflectors are supported by brackets 10', the said parts preferably being integral, as shown. The lower ends 10^a, are threaded for screwing on to the top-ends 9^c of the valve-bodies (see Fig. 5). The jets 9 may be integral parts of the arms 10^a, as shown. The jet-burners 9 all yield direct heat to the underside of the boiler 8, while the jets 3^f directly heat the vaporizer 5, after which the unabsorbed heat from these jets ascends towards the central bottom portion of the boiler, which is not directly heated by the jets 9. By this construction and arrangement of the burner and the several jets, a relatively large boiler surface may be effectually and evenly heated. The heating capacity of the burner may be enlarged by increasing the number of the jets 9, which receive the vapor from the annular reservoir 3, and these jets may be operated either singly or in multiples, at will, by means of the several cocks 9^e.

The operation of my improved kerosene burner is as follows: To start the burner, the cocks 9^e should all be shut off, as shown in Fig. 1. The operator should then turn a small quantity of the kerosene 7 into the chamber 5^a of the vaporizer, as shown in Fig. 4, after which the supply of the kerosene should be temporarily shut off. A suitable quantity of the alcohol 2^x should next be poured into the pan 2 and lighted. It generally requires two or three minutes for the burning alcohol to properly heat-up the metal of the superposed burner parts. At the end of this interval, the kerosene 7 in the chamber 5^a usually begins to vaporize, and the vapor passes down through the pipe 4 and into the arms 3^b—3^c, and escapes through the two normally open jets 3^f. This initial vaporizing of the oil 7 generally takes place before the alcohol flames die out, and the latter invariably ignites the vapor at the jets 3^f. The operator should then open one or more of the jets 9, and at the same time adjust the supply valve (not shown) carried by the pipe 6, so as to provide a steady feed of the kerosene 7 to the chamber 5^a, for the duration of the heating period. The liquid fuel delivered to the vaporizer 5 should never be allowed to overflow the top-end of the pipe 4 and flood the passages 3^a of the reservoir and the arms 3^b—3^c. It is the intention of the present invention to effect the vaporization of the kerosene entirely within the chamber 5^a, which is preferably positioned at such an elevation above the reservoir 3, as to co-operate with the discs 10 for properly and evenly spreading the flames and heat which ascends to

wards the boiler 8. In order to accomplish this vaporization safely and economically, the level of the kerosene in the chamber 5^a should be maintained slightly below the top-
5 end of the pipe 4, as shown in Fig. 4. By disposing the vapor feed pipe 4 at the center of the reservoir 3, whereby it is completely surrounded by the jets 3^c and 9, the temperature of the vapor is maintained at a high
10 degree until it reaches the said jets. This insures a more perfect combustion of the vapor and prevents waste of the fuel as well as the disagreeable odors common to kero-
15 sene burners. At the end of the heating pe-
riod, the operator simply shuts off the sup-
ply of the kerosene to the chamber 5^a and also closes the several jets. In a few minutes
20 the generation of the inflammable vapor will cease, and the flames at the several open jets will die out, without further attention or care.

Having thus described my invention, what I claim as new and desire to secure by Letters Patent, is—

25 1. A kerosene burner, including a hopper-like base, an annular reservoir mounted on said base, hollow radial arms bridging the central opening in the reservoir and communicating therewith, a hollow vapor-
30 izing member disposed above and parallel to the reservoir and registering with one of said radial arms, a vertical conduit connecting said member with all of said radial arms, the said radial arms having jets adapted to
35 heat said member for vaporizing liquid fuel, jet-burners mounted on said reservoir and partially encircling said member, and cocks for controlling said jet burners.
40 2. A kerosene burner including an annu-
lar reservoir, hollow radial arms bridging the central opening of said reservoir and communicating therewith, a hollow vaporizing member disposed above and parallel to the reservoir and registering with two align-
45 ing radial arms, a vertical gas conduit con-

necting said member with all of said radial arms, and a plurality of jets for heating said member.

3. A burner for heating boilers and the like, comprising an annular reservoir hav-
50 ing a plurality of jets for burning vapor, hollow arms extending radially across the central opening in said reservoir and com-
municating with the reservoir and with each other, a hollow pedestal rising from the
55 point of convergence of the said arms and communicating therewith, a hollow vapor-
izing member mounted on said pedestal adapted to discharge vapor downwardly
through said pedestal into said arms to be
60 distributed to different parts of said reser-
voir, and jets carried by registering arms for directly heating said vaporizing member.

4. In a burner for heating boilers and the like, a hopper-like fire-pan, an annular reser-
65 voir disposed in the top of the fire-pan and having a number of jet burners, hollow arms disposed diametrically across the opening in the reservoir and provided with gas-jets, a hollow pedestal rising from and communi-
70 cating with the converging ends of said arms, and a hollow member mounted on said pedestal adapted to vaporize oil when heated by the said gas-jets.

5. In a fuel-oil burner, a hopper-like fire-
75 pan, an annular reservoir disposed hori-
zontally over the mouth of the pan and having a plurality of gas-jets rising from its top side, flame-and-heat deflectors disposed co-
axially above said gas-jets, hollow radial
80 arms bridging the opening in said reservoir and converging at the center of said opening, gas burners carried by said arms, a vapor-
izer disposed parallel to said arms and re-
ceiving heat from the said gas burners, and
85 a hollow pedestal for elevating said vapor-
izer to substantially the same plane as said deflectors.

In testimony whereof I affix my signature.

CHARLES H. LEWIS.
